228,911

INSECT REPELANT CONTAINER OR SIMILAR ARTICLE

Adelaide L. Gatter, House Springs, Mo.
(2801 Locust St., St. Louis, Mo. 63103)

Filed Jan. 31, 1972, Ser. No. 222,435

Term of patent 14 years

Int. Cl. D23—04

U.S. Cl. D23—150

FIG. 1

FIG. 2

FIG. 1 is a top perspective view of an insect repellent container or similar article showing my new design; and FIG. 2 is a bottom perspective view showing the sides not seen in FIG. 1.

I claim:

The ornamental design for an insect repellent container or similar article, as shown.
